UNITED STATES PATENT OFFICE.

SAMUEL WILLENS, OF CHICAGO, ILLINOIS.

MAILING-FOLDER.

1,130,782.

Specification of Letters Patent. Patented Mar. 9, 1915.

Application filed April 29, 1914. Serial No. 835,167.

To all whom it may concern:

Be it known that I, SAMUEL WILLENS, a citizen of the United States, residing in Chicago, in the county of Cook and State of Illinois, have invented, a certain new and useful Improvement in Mailing-Folders, of which the following is a specification.

My invention relates to mailing devices, more particularly mailing folders or inserts employed for advertising purposes, which by means of springing the main leaf is made to apparently show action on a picture printed thereon, and which possesses a peculiarly secure-locking arrangement directly at the place of action in the picture.

The preferred form of my invention is illustrated in the accompanying drawings, in which—

Figure 1 is a perspective view showing the folder folded and locked in condition ready for mailing by the sender. In this view I show a picture of a closed eye on the side of the folder. The picture or its position may be varied to suit the desire of the advertiser or user. Fig. 2 is a perspective view showing the transverse edges of the same folded folder forced toward each other by springing the main leaf, which movement opens the eye and unlocks the folder. Fig. 3 is a perspective view of one surface of the opened folder shown in Figs. 1 and 10. Fig. 4 is a perspective view showing another form of the folder folded and locked in condition ready to mail. In this view I show a picture of a scarecrow on the side of the folded folder. Fig. 5 is a perspective view of the same folded folder showing its two vertical edges forced toward each other by springing the main leaf, which movement changes the picture to a well dressed man and unlocks the folder. Fig. 6 is a transverse sectional view of the folded device shown in Fig. 1 on the line 6—6. Fig. 7 is a transverse sectional view of the folder shown in Fig. 2 on the line 7—7, showing the main leaf sprung ready to disengage the lock. Fig. 8 is a transverse sectional view of the folder shown in Fig. 4 on the line 8—8. Fig. 9 is a transverse sectional view of the folder shown in Fig. 5 on the line 9—9. Fig. 10 is a perspective view of the same folder shown in Fig. 1, but with reverse method of locking. The action of the eye is just the reverse of the eye shown in Fig. 1. Fig. 11 is a perspective view of the folder shown in Fig. 10, showing the main leaf

sprung, forcing the transverse edges of the folder toward each other, which movement closes the eye and releases the lock. Fig. 12 is a transverse sectional view of the folder shown in Fig. 10 on the line 12—12. Fig. 13 is a transverse sectional view of the folder shown in Fig. 11 on the line 13—13 showing the main leaf sprung, and the transverse edges of the folder forced toward each other ready to disengage the lock. Fig. 14 is a perspective view of the reverse side of the open folder shown in Fig. 3, showing more clearly, the arrangement of the slits B¹ and C¹. Fig. 15 is a perspective view of another form of the folder having but two leaves, folded and locked ready for mailing. Fig. 16 is a transverse sectional view of the closed folder shown in Fig. 15 on the line 17—17.

The different portions are indicated by similar reference characters throughout the views.

In the forms of the folder shown in Figs. 1 to 13 inclusive, the folder consists of three leaves, the main leaf A, and the adjoining leaves B and C. The folder may consist of more leaves if desired. The leaf B has a slit B¹, and the leaf C has a slit C¹, in such position as regards the folds B² and C² that when folded, the tongue C³ formed by the slit C¹ on leaf C, will fit into slit B¹ on leaf B, thus locking the folder. The leaf B is of a length transverse to the folds B² and C², sufficiently less than leaf A, to allow springing the leaf A the proper distance to operate the lock and cause apparent action on pictures C⁴ and B⁴. It is preferable to have leaf A of a length transverse to the folds B² and C² so that the edge B⁵ of leaf B when in contact with fold C², just prevents the folder from unlocking. The slit C¹ may be either generally curved or channel shaped with the crown of the curve or channel toward the adjacent fold C² while slit B¹ may be either straight or curved as may be exigent, so that in locking the folder, the tongue C³ slides into slit B¹ in a direction opposite to the direction of the leaves B and C when in the act of unfolding, thus securing an exceptionally firm and novel lock for the folder.

A picture C⁴ may be painted, printed, pasted or stamped over or adjacent to slit C¹ and another picture B⁴ relating to said picture, painted, printed, pasted or stamped over slit B¹ on the same side of the open folder so that when the folder is operated,

a slight reciprocal pressure on folds B^2 and C^2 causes the pictures B^4 and C^4 to work in conjunction either to indicate action or entirely change.

5 In the forms shown in Figs. 15 and 16 the folder consists of two leaves, the main leaf C and the narrower adjoining leaf B, the leaf C having slit C^1 and the leaf B slit B^1 . Pictures, one on each surface of the 10 open folder or one on but one surface, may be printed, painted, pasted or stamped directly over or adjacent said slits, and the mutual operation of said slits and pictures are exactly as hereinbefore described in the 15 multi-leaved folder.

Operation: Take open folder of the forms shown in Figs. 1 to 9 inclusive, fold on the folds B^2 and C^2 which are usually parallel to each other and transverse to the open ends 20 of the folder, so that leaf C is in front of leaf B. Where the changeable picture is used, fold so that the pictures B^4 and C^4 face the outside of the folder. Now bend tongue C^3 toward the inside of the folder so 25 that it will slip into slit B^1 , straightening the tongue C^3 to the same plane as leaf C after insertion is made, thus effectively locking the folder. In the open folder of the 30 forms shown in Figs. 10 to 13 inclusive, fold so that leaf B is in front of leaf C. Then tongue C^3 should be bent toward the outside of the folder so that it will slip into slit B^1 on leaf B, after which the tongue is straightened to the same plane as leaf C, thus 35 securing the folder. The folder is just as securely locked in either method. Where pictures are used in connection with the lock, they will usually have reference to the 40 printed or written matter contained on the folder. To operate the picture and open the folder of the forms shown in Figs. 1 to 13 inclusive, place the thumb of the hand along one closed edge of the folder and the four 45 fingers on the far opposite edge and press slowly together until leaf A is sprung in the position shown in Fig. 2. In the open folder of the form shown in Figs. 15 and 17, fold on the fold B^2 so that leaf B is in front of leaf C. The method of closing the folder 50 and the operation of the lock, and picture, are exactly as hereinbefore described for the multi-leaved folder.

It will be seen that a device embodying this invention has great advantages:—First, 55 it will remain securely closed in the mail; second, on account of the changeable picture it will be saved and shown to others, thereby increasing its advertising value; third, the changeable picture is a material advantage 60 in expression, enabling the illiterate, as well as the educated, to understand the intent of the folder; fourth, it requires no clips or pasters to securely close the folder; fifth, its simplicity of manufacture; sixth, its simplicity of operation; seventh, it can be used 65

as a novelty with or without advertising matter; eighth, it can be used as an insert into an envelop.

What I claim as new and wish to secure by Letters Patent is:—

1. A folder having a main leaf which is adjoined on two opposite sides by leaves, the adjoining leaves being of a width transverse to the folds less than that of the main leaf, one leaf of which has a generally channel or arch shaped slit forming a tongue, the crown of said slit being toward the adjacent fold, another leaf having a slit designed to receive said tongue in a direction opposite to the action of the leaves in opening said folder, forming a lock for the folder, the narrower adjoining leaves permitting the two folded edges of the main leaf to be forced toward each other for the purpose of unlocking the folder. 70

2. A folder having two or more leaves, one end leaf of which has a generally channel or arch shaped slit forming a tongue to be used as one member of the folder's lock, the crown of said slit being toward the adjacent fold, another leaf having a slit designed to receive said tongue, a picture imprinted directly over or adjacent said slit, said picture designed and placed so as to apparently move, disappear, or change 90 when operating the lock. 95

3. A folder having two or more leaves, one end leaf of which has a generally channel or arch shaped slit forming a tongue, the crown of said slit being toward the adjacent fold, another leaf having a slit designed to receive said tongue, both slits mutually forming a lock, and pictures directly relating to each other, imprinted directly over or adjacent each slit, said pictures designed and placed so as to apparently create action, disappear or change when operating the lock. 100

4. A folder having two or more leaves, one leaf of which has a generally channel 110 or arch shaped slit forming a tongue, the crown of said slit being toward the adjacent fold, the tongue to be used as one member of the folder's lock, another leaf being wider between the folds than any of the 115 others, permitting the folded edges of the latter mentioned leaf to be forced toward each other, for the purpose of unlocking the folder.

5. A folder having a main leaf which is 120 adjoined on two opposite sides by leaves, the adjoining leaves being of a width transverse to the folds less than that of the main leaf, one adjoining leaf of which has a generally channel or arch shaped slit forming a tongue, the crown of said slit being toward the adjacent fold, and another leaf having a slit designed to engage said tongue 125 forming a lock which opens in a direction opposite to the action of the leaves in open- 130

ing the folder, the adjoining leaves being of width between the folds less than that of the main leaf, permitting the two folded edges to be forced toward each other, for the purpose of unlocking the folder.

6. A folder having two or more leaves, one leaf of which has a generally channel or arch shaped slit, forming a tongue, the crown of said slit being toward the adjacent 10 fold, another leaf having a slit adapted to engage said tongue forming a lock which opens in a direction opposite to the action of the leaves in opening the folder, and pic-

tures directly relating to each other, imprinted directly over or adjacent each fold, 15 said pictures being designed and placed so as to apparently create action in the pictures, or cause them to disappear or change their appearance when operating the lock.

In testimony of which invention, I have 20 hereunto set my hand.

SAMUEL WILLENS.
